US00D766916S

(12) **United States Design Patent** (10) **Patent No.:** **US D766,916 S**
Bertnick et al. (45) **Date of Patent:** **** Sep. 20, 2016**

(54) **DISPLAY SCREEN WITH GRAPHICAL USER INTERFACE**

(71) Applicant: **Symantec Corporation**, Mountain View, CA (US)

(72) Inventors: **Joe Bertnick**, Houston, TX (US); **Shubhabrata Mohanty**, Maharashtra (IN); **Peggy J. Kirk**, Ben Lomond, CA (US)

(73) Assignee: **Symantec Corporation**, Mountain View, CA (US)

(**) Term: **14 Years**

(21) Appl. No.: **29/475,328**

(22) Filed: **Dec. 2, 2013**

(51) LOC (10) Cl. **14-04**

(52) U.S. Cl.

USPC **D14/485**

(58) **Field of Classification Search**

USPC **D14/485-490**

CPC **G06F 3/0482; G06F 3/04842; G06F**

3/04817
